LAMINATED TUBE

John F. Levan, Elkhart, Ind., assignor to Excel
Curtain Company, Elkhart, Ind., a corporation
of Indiana

Application July 28, 1938, Serial No. 221,777

1 Claim. (Cl. 138—64)

This invention relates to tubes used primarily for rails, hand-holds, uprights, tubular framing for different articles, as for cots, chairs, seats, etc., or in any situation where a tube with an outer, smooth, polished or lustrous surface is desired, or to tubes of the type shown in my pending application, Serial No. 187,030, filed January 26, 1938, and has for its object the formation of a particularly strong rigid lock seam joint between the edges of an outer veneer strip of a finishing metal, as stainless steel, which joint is snugly wedged in the slot of an internal body tube and strengthened by internal corrugations or internal knurling which so additionally interlocks the laminations of the lock seam joint, as to make the joint a substantially rigid rod to resist torsional distortion.

The corrugation or knurling feature is shown as applied to the tube of my pending application referred to.

The invention also has for its object the method of forming the tube with the corrugated or knurled joint.

The invention consists in the novel features and in the combinations and constructions and in the method hereinafter set forth and claimed.

In describing this invention, reference is had to the accompanying drawing in which like characters designate corresponding parts in all the views.

Figure 1 is a fragmentary isometric view, on an enlarged scale, of a tubing embodying this invention.

Figure 2 is a similar view but showing the outside of the joint, after being finished.

Figure 3 is a longitudinal sectional view on line 3—3, Figure 1.

Figure 4 is a fragmentary sectional view through the joint prior to being corrugated or knurled.

The tube here illustrated comprises an inner tubular body 1, an outer veneer strip 2 of a metal, as stainless steel, capable of receiving and maintaining a high lustrous finish, and a reinforcing strip 3 for the veneer strip, this being of a softer, tougher metal than the veneer strip. The outer strip 2 and the intermediate strip 3 are coextensive and have their margins nested together by a lock seam joint.

The body 1 may be of any suitable thickness of relatively cheap metal, and is divided or slotted longitudinally with the edges 4 on opposite sides of the division or slot spaced apart to provide a recess for the lock seam joint.

The strips 2, 3 are divided longitudinally and

are substantially coextensive with each other. Their margins on one side of the line of division of said strips are folded reversely and nested to form a hook-shaped loop at 5 and the other margins of said strips are folded and nested together to form a hook-shaped loop 6. The two loops are hooked together to form a lock seam joint consisting of layers of stainless steel and the steel of softer, tougher metal. The first layer, toward the center of the tube, being of the softer, 10 tougher metal. When so folded and hooked together, the lock seam joint is located in the slot of the body 1, and as seen in Figure 4, bulges into the interior of the body 1 beyond the inner surface thereof, before the tube is completely formed into the form shown in Figure 1. Then the joint so consisting of laminations is provided with transverse corrugations 7, these being formed by a knurling operation with a tool applied to the innermost lamination within the 15 tube, so that the corrugations or knurling are exposed on the interior of the tube and the outside of the tube is smooth. The corrugations, as seen in Figure 3, become of less depth and greater 20 width from the interior of the tube toward the outer surface, and there are practically no corrugations in the outer surface of the stainless steel tube 2 adjacent the edge 8 of the joint. 25

The corrugating or knurling operation compresses the joint and wedges it tightly in the slot 30 and also closes up the joint at 8 to the smallest possible crevice. The joint thus formed, and by reason of the corrugations, is particularly strong to resist torsional strains applied to the tube, without welding and the consequent slight discoloration of the stainless steel, due to the heat 35 of the welding, and additional operations to eliminate such discoloration.

The method consists in performing the corrugating or knurling operation, after the tube has 40 been formed up into the form shown in Figure 4, the knurling to be applied to the inner face of the joint while pressure is applied to the outer face of the joint, causing the joint to be flattened and the laminations thereof interlocked by the corrugations. The tube is formed by passing two flat strips which form the layers 2, 3, flatwise on each other through rollers or dies which partly 45 form them with marginal nested flanges which eventually are interlocked and form the lock seam joint in the finished article. After the marginal flange forming operation, a flat strip which forms the backing 1 is fed flatwise onto the two strips between the marginal flanges. Then the three strips lying flatwise on each other are 50 55

fed through a series of dies or rollers which roll them up into tubular form and interlock the lock seam flanges of the layers 2, 3 between the edges of the body 1. After this operation, the tube is 5 in the form shown in Figure 4, and then the corrugating or knurling operation is performed which flattens the lock seam joint into the position shown in Figure 2 and firmly wedges and unites it in the lengthwise slot in the backing 10 1, making the whole practically an integral structure. The forming dies and knurling tool are arranged in series and series of operations are performed in a machine in which the flat strips are fed in at an end and the finished tube emerges 15 at the other end.

The tube, due to the corrugations, is stronger

at the joint and resists any torsional strains to which it is subjected in the use thereof, and in fact, the corrugations make the joint practically a solid rod wedged into the slot of the innermost tube 1.

What I claim is:

A tube construction comprising an inner tubular body slotted longitudinally and an outer veneer strip of a finishing metal having its margins interlocked together in a lock seam joint 10 consisting of layers, the joint being located in the slot and formed with internal transversely extending corrugations exposed on the interior of the tube leaving the outside of the tube smooth.
